United States Patent Office

Des. 222,131
Patented Oct. 5, 1971

222,131

PORTABLE CART

Raymond E. Benson, Robert L. Baumgartner, and Jay A. Wickum, Forest Park, Ill., assignors to Thomas Truck & Caster Co.

Filed Apr. 24, 1970, Ser. No. 22,633

Term of patent 14 years

Int. Cl. D12—02

U.S. Cl. D14—3

Fig. 1

Fig. 2

Fig. 3

FIG. 1 is a perspective view showing the rear and one side of a portable cart embodying my ornamental design;

FIG. 2 is a front elevational view of the cart shown in FIG. 1; and

FIG. 3 is an elevational view of the opposite side of the cart shown in FIG. 1.

We claim:

The ornamental design for a portable cart, as shown.
